(54) **CEMENT, HYDRAULIC**

(76) Inventor: **John White**

John White of Syracuse, State of New York.

Letters Patent.

The Schedule referred to in these Letters Patent and making part of the same containing a description in the words of the said John White himself, of his improvement in the application of Hydraulic cement to the making of coffins.

Whereas I John White of Syracuse in the county of Onondaga and State of New York did in conjunction with Daniel Dayton and Abram Hoyt both of the same State obtain Letters Patent of the United States, bearing date the eighth day of June Eighteen hundred and thirty five, for an invention in making and constructing coffins from American or Hydraulic Cement, and whereas I did in my own name obtain Letters Patent of the United States for certain improvements theron, which Letters Patent bear date the twenty fifth day of July eighteen hundred and thirty five. Now be it known that I the said John White have since the dates of the above named Patents, made for these improvements in making such coffins, and I do hereby declare that the foregoing is a full and exact description thereof.

My improvement consists in the employing of any of the known Hydraulic Cement, materials, mortars, which will consolidate into a substance resembling stone, under whatever name the same may be known, if prepared from Hydraulic lime, or whether the same may be prepared by the calcination, and combination of such materials, as will produce an analogous cement without powder, of Native Hydraulic Lime. In the formation of such Coffins I prefer by any of the methods referred to in the above named Letters Patent or by any other producing a like effect.

All that I claim under the foregoing specification, and will be entitled by Letters Patent is the right to employ any of the known Hydraulic cement materials as aforesaid, not included in the before mentioned Patents, in the making of receptacles for the dead, constructing the same in any

form or shape which may be desired convenient or desirable.

Witness, B. R. Morell,
James Brown,
